UNITED STATES PATENT OFFICE.

HERBERT W. CHENEY, OF NORWOOD, OHIO, ASSIGNOR, BY MESNE ASSIGNMENTS, TO
ALLIS-CHALMERS MANUFACTURING COMPANY, A CORPORATION OF DELAWARE.

POTENTIAL STARTER FOR ALTERNATING-CURRENT MOTORS.

1,125,004.

Specification of Letters Patent.

Patented Jan. 12, 1915.

Application filed June 7, 1905. Serial No. 284,162.

To all whom it may concern:

Be it known that I, HERBERT W. CHENEY, a citizen of the United States, residing at Norwood, in the county of Hamilton and 5 State of Ohio, have invented certain new and useful Improvements in Potential Starters for Alternating-Current Motors, of which the following is a full, clear, and exact specification.

10 My present invention relates to starting devices for alternating current motors and more particularly to devices for starting poly-phase motors of the induction type by varying the potential impressed upon the primary winding of the motor.

15 The object of the invention is to simplify the construction and arrangement of a potential starter and to produce one which is efficient and effective in its operation and 20 which, without change in its construction and without the substitution of parts, is adapted for use in connection with two-phase and three-phase systems of distribution.

25 The invention therefore consists of improvements in a system of control for alternating current motors, and also improvements in the construction and arrangement of parts of a potential starter 30 which will be hereinafter described and more particularly pointed out in the appended claims.

In the accompanying drawings, which 35 illustrate the preferred embodiment of my invention, Figure 1 is a longitudinal sectional elevation of the potential starter on the line 1—1 of Fig. 2; Fig. 2 is a sectional elevation of same on line 2—2, Fig. 1; Fig. 3 is an exterior view of a slightly modified form 40 of the starter in side elevation; Fig. 4 is an exterior view of the starter of Figs. 1 and 2 in front elevation; Fig. 5 is a diagrammatic representation of my improved potential starter, used in connection with a three-phase system; Figs. 6 and 7 are diagrams of 45 the connections made by the starter in Fig. 5 in the starting and running positions, respectively; Fig. 8 is a diagrammatic representation of the starter used in connection 50 with a two-phase system; and Figs. 9 and 10 are diagrams of the connections made by the starter in Fig. 8 in the starting and running positions respectively.

Referring to Figs. 1 to 4 inclusive, the 55 two single coil transformers 12 and 12^a each

consist of the windings 13 and cores 14 mounted in frame 15. The windings of the two transformers 12 and 12^a when connected for a three-phase system, may be considered together as forming V-connected auto-transformer windings. This frame 15 is supported on the bolts 16 fastened to the bracket 11, which also carries the casing cover 17. Suspended from said bracket is a controlling switch B. This switch comprises the contact fingers a and the drum 20 carrying the contact segments b. The drum 20 is rotatably mounted on a stationary stud or spindle 20^a held rigidly in the ends of the downwardly projecting lugs 23 and 24 respectively. These lugs may be integral with or otherwise fastened to the bracket 11. Mounted upon the insulating blocks 26 also suspend from said bracket are the contact fingers a which are adapted to coact with the contact segments b in a manner to be hereinafter described. These contact fingers are connected with the motor terminals and transformer terminals and taps from said transformers by the leads d, only part 80 of which are shown in Figs. 1 and 2, the most of said leads being omitted for the sake of clearness of illustration. Some of these leads are directly connected to the transformer windings within the casing and 85 some pass out of the casing through insulating bushings in openings formed at 27 in the sides of the bracket 11, (as shown in Figs. 1, 2, and 4.)

In the modification shown in Fig. 3 the 90 leads pass out of said casing through the rear of bracket 11 (as shown at 28 in Fig. 3.)

Mounted upon the drum 20 is a gear-wheel 29 which meshes with an idler gear 95 30 which in turn meshes with the gear 31 mounted upon the horizontally projecting shaft 32 in bracket 11. The shaft 32 is provided with the double operating handle 33 carrying the index fingers 34, which point 100 to the projections 35, 36, and 37 on the face of bracket 11, indicating respectively the "off," "starting," and "running" positions of the controlling switch.

As is very undesirable in starting devices 105 for alternating current motors which vary the potential impressed upon the primary winding of the motor, to throw the controlling switch from the running position back to the starting position when the motor is 110

running at its proper speed, I provide mechanism for constraining the operating shaft to move always in one direction in operating the potential starter from the running position. This mechanism comprises the ratchet wheel 38 mounted upon shaft 32 and having coöperating therewith the spring-pressed pawl 39. As here shown some of the teeth upon said ratchet wheel 38, namely, teeth 38^a which correspond to the "off" and "running" positions, are so constructed that the operating shaft is constrained to move in a clock-wise direction when leaving the "off" and "running" positions. The remaining teeth 38^b, corresponding to the "starting" positions, are so arranged as to permit the drum to be moved freely in either direction from the starting positions. It is sometimes desirable to return immediately to the "off" position from the "starting" position. In Figs. 1 to 4 inclusive, the starter is shown in its "off" position, the operating handle being horizontal. As the handle is moved in a clock-wise direction and the index fingers 34 point to the projections 36, the drum 20 is moved into the starting position. A further movement in the same direction, until the index fingers point to projections 37 brings the drum into the "running" position. A further movement in the same direction brings the handle again into the horizontal position and the drum 20 into its "off" position, 180° removed from its initial position. A further movement of 180° in the same direction will move the drum again through "starting" and "running" positions and said drum will be returned to its initial "off" position. To accomplish this controlling operation by 180° movement of the drum and operating handle, I mount the contact fingers on both sides of the horizontally arranged drum and arrange the contact segments on opposite sides of said drum in exact duplicate.

The controlling drum and contact fingers are preferably arranged to operate in an oil bath and for this purpose the oil tank 40 is provided. This tank contains oil preferably up to the level 41 and the drum is completely immersed in the oil. The tank is suspended from bracket 11 by any desirable means, preferably by the pivoted bolts 42 as shown in Figs. 2, 3, and 4.

By referring to Figs. 5 and 8, it will be seen that the controller drum (here shown in development) is provided with two duplicate sets of straight bridging contact segments b^1 , b^2 , b^3 , and b^4 , the segments b^1 and b^2 of each set corresponding to the starting position indicated by the vertical lines S and the segments b^3 and b^4 of each set corresponding to the running position indicated by lines R. These segments co-operate with the contact fingers a^1 to a^{12} in-

clusive in various operative positions of the controlling switch. The controlling switch in Fig. 5 is arranged to connect the transformers 12 and 12^a and the three-phase motor M to the mains f, g, and h of a three-phase system of distribution. The controlling switch in Fig. 8 is arranged to connect the transformers 12 and 12^a and the two-phase motor M¹ to the mains k, m, n, and p of a two-phase system of distribution. In either case the transformers 12 and 12^a are the same and taps are brought off at the intermediate points 45 and 45^a. The controller drums and fingers are also the same in each case. The only thing necessary to adapt my improved starter to a three-phase or a two-phase system is to change the leads at a few of the contact fingers as may be clearly seen by an inspection of Figs. 5 and 8. The finger a^9 is not employed in the three-phase connections.

When the controlling switch shown in Fig. 5 is moved into its starting position S, the segments b^1 and b^2 of one set are in engagement with the fingers a^1 , a^2 , a^3 , a^5 , and a^6 and the corresponding segments of the other set are in engagement with the fingers a^7 , a^8 , a^{11} , and a^{12} . This results in the connections clearly shown in Fig. 6, the transformer coils being V connected, or connected in open delta across the three-phase mains f, g, and h, and the motor M connected between the taps 45 and 45^a and the main h to which both transformer coils are connected. A potential lower than the potential of the mains is thus impressed upon the primary windings of the motor and same starts with considerable torque and a reduced flow of current in the secondary windings. When the controlling switch is moved into the running position R, the segments b^3 and b^4 of one set are in engagement with fingers a^2 , a^3 , a^4 , and a^5 and the segment b^4 of the other set is in engagement with the contact fingers a^{10} and a^{11} , giving the connections shown in Fig. 7. In this "running" position the transformer coils are completely cut out of circuit and the motor M is directly connected to the mains f, g, and h, thereby impressing the full potential of the mains upon the motor primary winding and increasing the speed of the motor. In passing to this position, the protective devices, or fuses x and y are connected in circuit to protect the motor against injury due to overload and excess current.

The connections made by the controlling switch in Fig. 8 may be traced readily on the diagram, the starting position giving the connections shown in Fig. 9, in which the transformer 12 is connected across one phase k, m of the two-phase system and the other transformer 12^a is connected across the other phase n, p, one phase of the motor 180

winding being connected between the tap 45 and one end of transformer 12, and the other phase of the motor being connected between the tap 45^a and one end of the transformer 12^a. In the running position the transformer coils are cut out of circuit and the motor is connected directly to the mains *k*, *m*, *n*, *p*, as shown in Fig. 10, and the fuses *x* and *y* are connected in circuit.

10. In the appended claims, I aim to cover all modifications of my invention which do not involve a departure from its spirit and scope.

Having thus described my invention, what 15 I claim as new and desire to secure by Letters Patent is—

1. In a potential starter, a bracket, transformers mounted upon said bracket, a controlling switch comprising a contact carrying drum and co-acting contact fingers supported by said bracket, a tank containing oil in which said controlling switch is immersed, a controlling handle geared to said drum, and ratchet and pawl mechanism for 25 constraining said handle to move always in the same direction from certain positions of said drum.

2. In a potential starter, a bracket, transformers mounted upon said bracket, a controlling switch comprising a longitudinally mounted contact carrying drum and co-acting contact fingers suspended from said bracket at opposite sides of the drum, an oil tank containing oil in which said drum and 35 said contact fingers are immersed, an operating shaft projecting horizontally from said bracket, a handle carried by said shaft, and gearing between said shaft and drum.

3. In a potential starter, a bracket, transformers mounted upon said bracket, a controlling switch comprising a contact carrying drum and co-acting contact fingers suspended from said bracket, a controlling handle geared to said drum, ratchet and 45 pawl mechanism for constraining said handle to move always in the same direction from certain positions of same, and a tank suspended from said bracket and containing oil in which said drum is immersed, the shaft 50 of said handle being above the level of the oil.

4. In a potential starter, a bracket, transformers mounted upon said bracket, a controlling switch comprising a contact carrying drum and co-acting contact fingers suspended from said bracket, a tank containing oil in which said controlling switch is immersed, an operating shaft geared to said drum, and ratchet and pawl mechanism for 55 constraining said operating shaft to move always in a forward direction from certain of the operative positions of the controlling switch.

5. In a potential starter, a bracket, transformers mounted upon said bracket, a con-

trolling switch comprising a contact carrying drum and co-acting fingers suspended from said bracket, a tank containing oil in which said controller is immersed, a controlling handle geared to said drum, and 70 ratchet and pawl mechanism for constraining said handle to move always in the same direction from certain operative positions while permitting said handle to move in either direction from other positions, the 75 contacts of said controlling switch and the operating mechanism therefor being so arranged that as the handle is moved forward through 180° the controlling switch passes successively into the "starting," "running," 80 and "off" positions.

6. In a potential starter, a controlling drum provided with a plurality of pairs of duplicate sets of straight bridging contact segments, and two sets of contact fingers 85 with either of which sets of fingers any set of said bridging contact segments may be made to coöperate.

7. In a potential starter, a controlling drum provided with duplicate sets of straight 90 bridging contact segments *b*¹ and *b*² in the starting position, and duplicate sets of straight bridging contact segments *b*³ and *b*⁴ in the running position, duplicate sets of contact fingers which simultaneously coöperate with either the two sets of contact segments *b*¹ and *b*² respectively or the two sets 95 of contact segments *b*³ and *b*⁴ respectively, either set of contact fingers being capable of coöoperating with any set of contact segments.

8. In combination, a supply circuit, an induction motor, auto-transformer windings, a controller in different positions connecting the motor to the supply circuit through the 105 auto-transformer windings, connecting the motor to the supply circuit directly, and disconnecting the motor, and means for preventing the controller from passing from the second of said positions directly to the 110 first.

9. In combination, a supply circuit, an induction motor, auto-transformer windings, a controller movable always in one direction and having positions for connecting the motor to the supply circuit through the auto-transformer windings, for connecting the 115 motor to the supply circuit directly, and for disconnecting the motor, and means for preventing the controller from passing from the last of said positions directly to the 120 second.

10. In a controller, the combination with two sets of contact fingers, of a rotatable drum having duplicate rows of starting contacts and duplicate rows of running contacts, and movable to bring either the rows of starting or running contacts into simultaneous engagement with said sets of contact fingers, any row of contacts being ar- 125 130

ranged to coöperate with either set of contact fingers.

11. In a controller, a rotatable drum, contact fingers coöperating with said drum, and means for preventing backward movement of the drum from a certain predetermined position while permitting backward movement from a certain other predetermined position and permitting forward movement from all of said positions.

12. In a controller having "off", "starting" and "running" positions, the combination with a rotatable contact-carrying member, of means for permitting motion of said member in one direction only from the "off" and "running" positions while permitting either backward or forward movement from "starting" position.

13. In a potential starter, the combination of a controlling drum provided with a plurality of sets of counterpart groups of straight bridging contact segments and a plurality of groups of contact fingers with any one of which groups of fingers any group of said bridging contact segments may be made to coöperate.

14. In a controller, the combination with a plurality of sets of contact fingers, of a rotatable drum having a plurality of counterpart rows of starting contacts and a plurality of counterpart rows of running contacts, said drum being movable to bring any row of contacts into engagement with any set of contact fingers, the different rows of starting contacts or of running contacts all engaging the respective sets of contact fingers simultaneously.

15. In a potential starter, the combination of a plurality of sets of contact fingers, a controlling drum provided with a plurality of counterpart sets of bridging contact segments, said drum being movable to make any set of contact segments coöperate with any set of contact fingers, and each set of contact segments being arranged to coöperate with sets of contact fingers in a plurality of positions in each of which each bridging contact segment extends in a straight line between all the fingers it bridges.

16. In a controller, the combination of a bracket, a controlling switch comprising a contact-carrying drum and co-acting contact fingers suspended from said bracket, a tank containing oil in which said drum is immersed, a controlling handle geared to said drum, and ratchet and pawl mechanism for constraining said handle to move always in the same direction from certain positions of said drum.

17. In a controller, the combination of a bracket, a controlling switch comprising a longitudinally mounted contact-carrying drum and co-acting contact fingers suspended from said bracket, the fingers being at diametrically opposite sides of the drum, an oil tank containing oil in which said drum and contact fingers are immersed, an operating shaft projecting horizontally from the bracket above the surface of the oil, a handle carried by said shaft, and gearing between said shaft and drum.

18. In a controller, the combination of a tank containing oil, a controller drum immersed in the oil in said tank, the shaft of said drum being substantially horizontal, contact fingers coöperating with said drum, an operating shaft substantially parallel to the shaft of the drum and above the surface of the oil in said tank, and gearing between said two shafts.

19. In a controller, the combination of a tank containing oil, a controller drum immersed in the oil in said tank, the shaft of said drum being substantially horizontal, sets of contact fingers diametrically opposite each other and coöperating with said controller drum, an operating shaft, a handle on said shaft above the level of the oil in said tank, and gearing between said operating shaft and the shaft of the controller drum.

In testimony whereof I affix my signature, in the presence of two witnesses.
